UNITED STATES PATENT OFFICE.

HERMAN PLAUT, OF NEW YORK, N. Y.

LIGHTING-FIXTURE.

1,247,000.

Specification of Letters Patent. Patented Nov. 20, 1917.

Application filed February 10, 1917. Serial No. 147,904.

To all whom it may concern:

Be it known that I, HERMAN PLAUT, a citizen of the United States, residing in the borough of Manhattan, city, county, and State of New York, have invented a certain new and useful Improvement in Lighting-Fixtures, of which the following is a specification.

My invention relates to lighting fixtures in which an incandescent electric lamp is inclosed in a globe or shade, preferably of a semi-transparent, diffusing character which is suspended below the ceiling and my object is to provide for illuminating the ceiling with a diffused, direct light and at the same time transmit some of the light by reflection into the room below the ceiling.

These and further objects will more fully appear in the following specification and the accompanying drawings considered together or separately.

I have illustrated my invention in the accompanying drawings in which like parts are designated by similar reference characters in all of the figures and in which;

Figure 1 is a half side elevation and half vertical section of one embodiment of my invention.

Fig. 2 is a sectional view of a modification, and

Fig. 3 is a detail sectional view of another modification.

In carrying out my invention I provide a gallery or crown 1 which is preferably of cylindrical form. The crown may be composed of any suitable material either transparent, semi-transparent or opaque in character and its exterior surface is preferably highly ornamental in character.

Supported within the crown in any desired manner is a bridge 2 to which is secured a lamp socket 3 of any known type, which carries a lamp 4. Also carried by the bridge 2 is a hickey 5 by means of which the fixture may be suspended from a chain, rod or by any other means.

Removably carried by the lower extremity of the crown 1 is an annulus 6 in which is supported a shade 7. The shade comprises a globe or bowl member 8 preferably of semi-transparent character so that some of the rays of light from the lamp 4 will pass through it and be diffused and some of the light will be reflected from its interior. The bowl or globe is provided with an extension 9 which in Fig. 1 is

shown as flaring. The extension is composed of crystal or transparent glass and is provided at its upper edge with a flange 10 which rests within the annulus 6. The globe 60 and extension are preferably of a single piece of transparent glass and the globe is rendered translucent or semi-transparent by a coating of enamel, by being ribbed, by a sand blast or by acid etching. 65

Resting within the crown 1 is a concave reflector 11, by means of which direct rays of light from the lamp and rays reflected from the globe 8 will be reflected downward through the transparent extension 9. The 70 reflector 11 is composed of glass which has been rendered diffusive by having one or both of its surfaces broken up, either by means of corrugations, sand blasting, acid etching or enameling. This will permit a 75 part of the light from the lamp and from the reflecting surface of the globe to pass through the reflector and be diffused upon the ceiling. The reflector is provided with an aperture at its center for the passage of 80 the socket 3.

If the crown 1 be transparent or semi-transparent in character, some of the light diffused by the reflector 11 will pass through it. 85

The annulus 6 is preferably secured to the crown 1 by means of screws 12 to admit of the ready removal of the globe and access to the lamp.

In the modification shown in Fig. 2 the 90 annulus 13 is hinged to the crown 1 and held in place by means of a catch 14. The reflector 15 is convex and extends downward into the extension 16 which in the modification is cylindrical instead of flaring. The 95 convex reflector will reflect some of the light in a horizontal direction and thereby spread it over a greater surface than where the reflector is concave. It will be understood that the form of reflector shown in 100 Fig. 2 may be employed in connection with the crown 1 and globe 8 of Fig. 1 or the crown 18^a and globe 26 illustrated in Fig. 3.

In the modification shown in Fig. 3 the bridge 17 is carried by a ring 18 which also 105 supports the crown 18^a which in the modification is shown as made of glass. Carried on the ring 18 by means of screws 19 is an annular shelf 20 on which is supported the diffusing reflector 21 and the transparent 110 extension 22, which is integral with the reflector. The extension 22 is provided with

a flange 23 on which a gallery 24 is supported by means of screws 25. A globe 26 is supported on the gallery.

The transparent extension is practically invisible and the globe has the appearance of being suspended in mid-air.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having now described my invention what I claim as new and desire to secure by Letters Patent is:—

1. A device of the character described, having a lamp and a support therefor, an open ended member carried by the support, a semi-transparent reflector carried by the member, below the support therefor, an annulus removably carried by the member, a semi-transparent globe, said globe having an integral transparent portion engaging and supported by the annulus, said reflector

extending within the transparent portion of the globe.

2. A device of the character described, having a lamp, a hanger for supporting the lamp, arms carried by the hanger, an open ended cylinder carried at the ends of the arms, said cylinder having an inturned integral flange at its lower extremity, a light transferring reflector supported on the flange, said reflector being located between the flange and the arms, an annulus removably carried by the member, a semi-transparent globe suspended in the annulus, said globe having an upper, flaring portion engaging the annulus, said flaring portion being integral with the globe and of transparent material, the central portion of said reflector extending within the transparent flaring portion of the globe.

This specification signed and witnessed this eighth day of February, 1917.

HERMAN PLAUT.
